UNITED STATES PATENT OFFICE.

ROBERT A. STEWART, OF MILWAUKEE, WISCONSIN.

ROTARY ENGINE.

1,222,046.

Specification of Letters Patent. Patented Apr. 10, 1917.

Application filed April 27, 1916. Serial No. 93,840.

To all whom it may concern:

Be it known that I, ROBERT A. STEWART, a citizen of the United States, residing at the city of Milwaukee, county of Milwaukee, 5 and State of Wisconsin, have invented new and useful Improvements in Rotary Engines, of which the following is a specification.

My invention relates to improvements in 10 rotary engines. The object of my invention is to provide an inexpensive rotary engine operating in part by impact of the motive fluid upon vanes carried by the rotor, but which can be easily and quickly started 15 and operated at slow speeds with reasonable efficiency, and with high efficiency at maximum speed.

In the drawings:—

Figure 1 is a central vertical sectional view drawn to a plane at right angles to the axis of rotation.

Fig. 2 is a longitudinal sectional view drawn to a vertical plane which includes the axis of rotation, but showing the shaft and 25 gearing largely in full.

Like parts are identified by the same reference numerals throughout both views.

An outer stationary cylindrical member 1 is mounted by a supporting base 2 and provided with a main inlet duct 3. A shaft 4 extends axially through the cylinder or casing 1 and supports a rotary member 6 within the casing. The casing is provided with a cylindrical partition 8 which encircles the rotary member 6, and between this partition 8 and the outer wall or periphery of the member 1 there is a cavity 10, annular in form and adapted to receive the motive fluids from the inlet 3 and distribute it to a 35 set of nozzle ducts 11 formed in the partition member 8. The rotary member 6 is provided with a series of vanes or buckets 13 which project outwardly from the periphery of the member 6 in the direction of 40 the cylindrical wall 8 and into close proximity thereto. These vanes or bucket flanges 13 may be of any desired form best adapted to receive the force of the motive fluid discharged against them through the nozzle 45 ducts 11, whereby the kinetic energy developed in said nozzle ducts may be utilized to drive the rotary member.

But instead of permitting the motive fluid to pass directly from the buckets 13 to the 55 outlet unrestrained, I allow a limited pres-

sure to build up in the space between the rotary member 6 and the surrounding stationary wall 8 and direct the motive fluid through a set of nozzle ducts 15 into a set of buckets 16 resiliently supported against the inner ends of the nozzle ducts 15. The buckets 16 are supported by levers, each lever being pivotally secured to one side wall of the member 6 by a fulcrum pin 18. One arm 19 of the lever is pivotally connected with the rear side of the bucket and another arm 20 receives the pressure of a coiled spring 21 interposed between it and a fixed bracket 22 also secured to the side wall of member 6. The pressure of the spring 21 is exerted 60 in a direction to force the buckets 16 against the discharge end of the nozzle 15 to which it pertains. The motive fluid after being discharged into the buckets 16 is delivered into the interior cavity 25 of the rotary member 65 from which it passes to the exterior, preferably through a duct 26 extending longitudinally through one end of the shaft 4. The motive fluid being allowed to enter this duct from the cavity 25 through 70 ports 28 in said shaft. The duct 26 may lead to any suitable point of discharge, preferably in a suitable condenser, (not shown). The opposite end of the shaft from that through which the motive fluid is delivered 75 is provided with a worm 30 in operative relation to a worm wheel 31, and adapted to drive the latter.

Any motive fluid may be employed to drive my improved engine. Where an elastic fluid is used the engine will start quickly owing to the fact that considerable pressure may be allowed to build up in the space between the rotary member 6 and the surrounding stationary wall or nozzle partition 8, and the pressure of the fluid will therefore be exerted through the nozzle ducts 15 directly against the buckets 16. As soon as the pressure becomes sufficient to force these buckets to open position they will thereafter 90 be held open by impact of the expanding particles or molecules of fluid, but in the meantime the rotary member will have been set in motion and the vanes 13 will thus become quickly effective to receive and utilize 95 the impact of the motive fluid discharged through the nozzle ducts 11, it being understood that in order to utilize the kinetic energy of a moving fluid to the best advantage the speed of the impact receiving 100

110

member must be approximately forty-seven per cent. (47%) of the speed of the motive fluid.

It is recognized that some loss of efficiency occurs by allowing pressure to build up in the space between the rotary member and the nozzle wall 8, but this loss is retrieved by utilizing the impact of the motive fluid against the buckets 16, and in addition there-
10 to I secure the advantages above described.

It will be observed that the nozzle ducts 15 project inwardly from the cylindrical outer wall of the rotary member at a tangent to a circle concentric therewith and which 15 includes the inner or discharge ends of said nozzle ducts, and the buckets 16 are so located as to receive the pressure of the fluid when in closed position or the impact of the fluid when in open position in substantially 20 the same direction taken by the fluid delivered through the nozzle ducts 11. The re-actionary pressure of the fluid in the nozzles 15 is, of course, exerted against the surrounding stationary wall 8.

25 I claim:—

1. A rotary engine comprising the combination of an outer casing, a stationary annular nozzle wall provided with nozzle apertures, a hollow rotary member mounted to revolve within said nozzle wall, and provided with an annular set of impact receiving vanes, a set of nozzle ducts leading inwardly through the peripheral wall of said rotary member, and a set of buckets resiliently mounted within said rotary member and adapted to close the outlets of said nozzle ducts, together with means for delivering motive fluid into said casing, and means for discharging it from within said hollow 40 rotary member.

2. A rotary engine including a rotary member provided with an interior cavity, a set of nozzles extending into said cavity at

a tangent to a circle concentric with the outer wall and coincident with the nozzle 45 outlets, and a set of buckets resiliently supported within said cavity and adapted to normally seat against the discharge ends of the nozzles, together with means for delivering motive fluid through said nozzles and 50 allowing it to escape from said cavity after being discharged into the respective buckets.

3. A rotary engine comprising the combination of a cylindrical casing having a double walled periphery, and provided with an annular fluid receiving chamber between said walls, the inner wall being also provided with nozzle ducts leading to the interior, a rotary member mounted within said casing and having a cylindrical wall concentric with the peripheral walls of the casing, a set of bucket flanges projecting outwardly from the cylindrical wall of the rotary member, a set of nozzle buckets projecting inwardly from the cylindrical wall of the rotary member at a tangent to a circle concentric thereto, and which includes the inner ends of said nozzle duct, a set of buckets resiliently supported from one side wall of the rotary member and normally closing the 70 inner ends of said nozzle ducts, means for delivering motive fluid through the outer peripheral wall of said casing, and a hollow shaft supporting the rotary member and extending through the casing, said shaft having apertures within the rotary member 75 communicating with the interior thereof, whereby the motive fluid may be permitted to escape through said shaft.

In testimony whereof I affix my signature 80 in the presence of two witnesses.

ROBERT A. STEWART.
